MOLD SHAKEOUT APPARATUS

Michael H. Kelly, Detroit, Mich., assignor to Kelsey-Hayes Wheel Company, Detroit, Mich., a corporation of Delaware

Application September 10, 1948, Serial No. 48,695

6 Claims. (Cl. 22—1)

1

The invention relates to mold shake-out apparatus and refers more particularly to apparatus for shaking out the molding sand from the molds and from the castings in the molding sand.

The invention has for one of its objects to provide an improved mold shake-out apparatus provided with means for shaking out the molding sand and removing a casting from the mold.

The invention has for another object to so construct the mold shake-out apparatus that the casting dumping device is not affected by the device for shaking out the molding sand.

The invention has for a further object to provide an improved mold shake-out apparatus in which the casting is discharged from the mold on to another portion of the shake-out device to further remove molding sand which might adhere to the casting when discharged from a mold.

With these as well as other objects in view, the invention resides in the novel features of construction and combinations and arrangements of parts as more fully hereinafter set forth.

In the drawings:

Figure 1 is a plan view of a portion of a conveyer system including a mold shake-out apparatus embodying the invention.

Figure 2 is an enlarged plan view of the mold shake-out apparatus.

Figure 3 is a front elevation thereof.

Figure 4 is an end view thereof, partly broken away.

Figure 5 is an elevation partly broken away of the eccentric for effecting the shaking out of the molding sand.

As illustrated in Figure 1, 1 is a conveyer for advancing in the direction of the arrow 2 the lower mold section or drag 3 containing molding sand and castings, the upper mold section or cope having been removed. 4 is a compressed air cylinder, the plunger of which is adapted to move the drag and its contained molding sand and castings on to the conveyer 5 which carries the drag and contained molding sand and castings to the shake-out apparatus 6 which is designed to shake-out the molding sand and discharge the castings from the drag after which the drag is discharged on to the conveyer 7 by the plunger of the compressed air cylinder 8.

The mold shake-out apparatus 6 comprises the shake-out device 9 and the casting dumping device 10. The shake-out device has the base 11, the main grate 2 and the side plates 13 to which the main grate is fixedly secured. Each of the side plates has secured thereto near its end the bracket 14 between the upper and lower flanges

2

of which are located the upper and lower rubber blocks 15 and 16. The base has the brackets 17 secured thereto with each bracket having a flange extending between the upper and lower rubber blocks. For effecting a rapid up and down motion of the main grate an eccentric device 18 is provided midway of the ends of the main grate, the eccentric device having the housing 19 extending through and secured to the side plates 13 and the eccentric 20 extending through the housing and journaled at its ends in the bearings 21 mounted on the base 11. Suitable bearings are provided between the eccentric and the housing and the eccentric is suitably rotated as by means including the pulley 22 secured to one end of the eccentric and driven by an electric motor connected to the pulley by a belt. The main grate 12 is longitudinally inclined so that any castings thereon will during the rapid up and down movement of the main grate travel downwardly along the same and finally drop off. This construction including the base, the main grate, the side plates and the eccentric device is a standard unit made by the Simplicity Engineering Company of Durand, Michigan. For receiving the drag with the contained molding sand and castings from the conveyer 5, I have provided the second grate 23 which is mounted on and extends over the main grate 12 for a part of its width. The second grate is formed of the bars 24 extending longitudinally of and welded to the main grate and the transverse bars 25 welded to the bars 24. The upper edges of these bars 24 and 25 are flush and form the surface for supporting the drag. This surface is inclined downwardly and inwardly so that when the drag is transferred by the conveyer 5 to the second grate the drag will move inwardly toward the longitudinal center of the shake-out device until it engages the stops formed by the upward projections 25' at the ends of the transverse bars 25.

The dumping device 10 comprises the L-shaped members 26 fixedly secured at longitudinally spaced points to the shaft 27 extending longitudinally of the shake-out device above the main grate and journaled at its ends in the bearings 28 which are mounted on the supporting frames 29 carried by the brackets 30 upon the base 11. Each L-shaped member 26 has the transverse arms 31 and 32, the arms 31 in the normal position of the dumping device extending through the vertical slots 33 of the longitudinal bars 24, these slots having open upper ends. Also in the normal position of the dumping device, the arms

31 are located below the supporting surface of the second grate and above the bottoms of the slots with sufficient clearance to provide for the rapid up and down movement of the second grate with the main grate without engaging the flask or the bottoms of the slots. In other words, the construction is such that the arms and consequently the rockable members are not affected by the movement of the grates. The arms 32 in the normal position of the dumping device extend upwardly and have at their outer ends the projections 34 providing stop shoulders for preventing the drag from sliding off the arms. For swinging the rockable members I have provided the compressed air cylinder 35 which is pivotally mounted on the fixed support 36 which is preferably secured to the floor. The piston rod 37 of the piston of the air cylinder is pivotally connected to the lever 38 which is fixed to an end of the shaft 27. The air cylinder is of standard construction and is cushioned at both ends with the cushion at the free end serving to locate the normal position of the rockable members 26. By admitting compressed air to the free end of the air cylinder the shaft 27 is rotated to swing the rockable members 26 so that their arms 31 will engage the drag 3 and swing the same upwardly and angularly to a substantially vertical position at which time the upper end portion of the drag hits the stop 39 which is in the nature of a rod extending longitudinally of and above the shake-out device. When the drag hits the stop the castings will be thrown out of the drag by reason of their momentum, and for the purpose of guiding these castings to the main grate 12 beside the second grate 23 I have provided the guide 40 which is in the nature of a plate extending over the adjacent side plate 13 and suitably mounted on the base 11 as by means of the uprights 41.

In operation it will be seen that when a drag with contained molding sand and castings is conveyed to the second grate 23 it will be moved downwardly over this grate to a position to engage the stops formed by the upward projections 25 of the transverse bars 25, both the main grate 12 and second grate 23 being given rapid up and down motion by the eccentric 20. After a suitable time interval, during which practically all of the molding sand is jarred from the drag and castings and dropped through the grates, compressed air is admitted to the free end of the air cylinder 35 and the rockable members 26 of the dumping device are swung to raise and swing the drag and castings until the drag assumes a substantially vertical position at which time it hits the stop 39 and the castings are discharged by reason of their momentum against the guide plate 40 and then directed on to the portion of the main grate 12 beside the second grate 23. Since this main grate has a rapid up and down motion and is also inclined longitudinally, molding sand adhering to the castings is dislodged and falls through the main grate and the castings are moved downwardly over the main grate and drop off its lower end. Compressed air is then admitted to the pivotal end of the air cylinder 35 and the rockable members 26 of the dumping device are returned to their normal positions. The drag 3 which is returned with the rockable members may then be transferred to the conveyor 7 by the plunger of the air cylinder 8.

What I claim as my invention is:

1. A mold shake-out apparatus comprising a

longitudinally inclined main grate, a second grate mounted on and extending over said main grate for a part of its width, said second grate having an upper surface for supporting a mold section containing a casting, means for shaking said main and second grates, a device having arms normally extending transversely of said second grate and occupying a position below said upper surface of said second grate, means for swinging said device in a direction moving said arms upwardly into engagement with the mold section and lifting the mold section and casting, means engageable with the lifted mold section holding the same on said arms and providing for discharge of the casting by its momentum, and a guide positioned in the path of movement of and engageable with the discharged casting to direct the same on to said main grate beside said second grate.

2. A mold shake-out apparatus comprising a main grate, a second grate mounted on and extending over a portion of said main grate, said second grate having an upper surface for supporting a mold section containing a casting, means for shaking said main and second grates, a device having arms normally extending transversely of said second grate and occupying a position below said upper surface of said second grate, said device being supported independently of said second grate, means for swinging said device in a direction moving said arms upwardly into engagement with the mold section and lifting the mold section and casting, means engageable with the lifted mold section holding the same on said arms and providing for discharge of the casting by its momentum and means positioned in the path of movement of the discharged casting and engageable therewith to direct the same on to said main grate.

3. A mold shake-out apparatus comprising a grate having an upper surface for supporting a mold section containing a casting, said grate having upwardly opening recesses, means for shaking said grate, a rockable device supported independently of said grate and having arms normally extending across a portion of said grate and occupying a position within the recesses and below said upper surface of said grate, means for swinging said device in a direction moving said arms upwardly into engagement with the mold section and lifting the mold section and casting, and stop means for limiting the swinging, said stop means being engageable with the mold section to hold the same on said arms and provide for discharge of the casting by its momentum.

4. A mold shake-out apparatus comprising a grate having an upper surface for supporting a mold section containing a casting, said grate having upwardly opening recesses, means for shaking said grate, a device supported independently of said grate and having arms normally extending across a portion of said grate and occupying a position within the recesses and below said upper surface of said grate, and means for moving said device in a direction raising said arms into engagement with the mold section and thereby raising the mold section and casting away from said grate.

5. A mold shake-out apparatus comprising a grate having an upper surface for supporting a mold section containing a casting, said grate having upwardly opening recesses, means for shaking said grate, an L-shaped device pivotally mounted independently of said grate and having arms normally extending across a portion of and

occupying a position within the recesses and below said upper surface of said grate, and means for swinging said device in a direction moving said arms upwardly against the mold section and raising the mold section and casting away from said grate.

6. A mold shake-out apparatus comprising a grate having transversely extending bars with substantially flush upper edges for supporting a mold section containing a casting, certain of said bars being provided with vertical slots having open upper ends, means for shaking said grate, a rockable device supported independently of said grate and having arms normally extending transversely of said grate within the slots and below the upper edges of said bars and means for swinging said rockable device in a direction

raising said arms and lifting the mold section and casting away from said grate.
